UNITED STATES PATENT OFFICE.

HOWARD D. COLMAN, OF ROCKFORD, ILLINOIS, ASSIGNEE, BY MESNE ASSIGNMENTS,
TO HOWARD D. COLMAN, LUTHER L. MILLER, AND HARRY A. SEVERSON, COPART-
NERS DOING BUSINESS IN ROCKFORD, ILLINOIS, AS BARBER-COLMAN COMPANY.

KNOT-STAGGERING MECHANISM.

1,070,116.

Specification of Letters Patent. Patented Aug. 12, 1913.

Application filed March 16, 1908. Serial No. 221,395.

To all whom it may concern:

Be it known that I, HOWARD D. COLMAN, a citizen of the United States, residing at Rockford, in the county of Winnebago and State of Illinois, have invented certain new and useful Improvements in Knot-Staggering Mechanisms, of which the following is a specification.

This invention relates to a mechanism for tying knots and for preventing alinement of two successively tied knots.

One of the objects of the invention is to provide means for staggering the successively formed knots resulting from the uniting of adjacent threads of two warps.

The invention herein shown may be applied to a warp-uniting machine of the type found in my British Patent No. 10,484, May 18, 1905. The machine shown in my said British patent unites corresponding threads from two adjacent warps so that the knots in the entire series are in alinement, therefore, when the uniting has been completed and the warp threads are to be drawn through the harness eyes, the drop wires, or both, all of the knotted ends come in contact with the edges of the harness eyes or drop wires at one time and in some instances they may not pass through the harness eyes as readily as they would if the knots were set off or staggered with relation to each other.

In the accompanying drawings, Figure 1 is a plan view of the tying mechanism, and the staggering elements cooperating therewith. Fig. 2 is a sectional view through a pair of warp frames operating in conjunction with the tying mechanism, the ends of the staggering elements being shown as acting upon the warp threads. Fig. 3 is a plan view of the united portions of an old and new warp. Fig. 4 is an elevational view of the gearing for actuating the tying mechanism. Fig. 5 is a plan view of the staggering members, showing one of the arms projected its full stroke. Fig. 6 is a similar view of the staggering members showing one arm at about two-thirds its full stroke and the other arm at about one-third its full stroke. Fig. 7 shows the arms reversed as to their positions in Fig. 6. Fig. 8 is an end view of the tying-bill barrel; and Fig. 9 is a longitudinal sectional view through the barrel showing the tying-bill and its bill spring in elevation.

The warps *a* and *b* carried by the frames 55 A and B may be presented to the uniting mechanism in any suitable manner.

In order to assist in a proper understanding of the invention I shall use the same reference numerals on the drawings in this case as are used on corresponding parts in said British Patent No. 10,484 of 1905.

The frame A comprises the clamps 20 and 28 in which the new warp *a* is rigidly secured. The frame B comprises clamps 37 65 and 38 for the old warp *b*. The mechanisms for selecting corresponding threads from the warps *a* and *b*, for severing the selected threads to provide loose ends, for tying the loose ends together, and for disposing the 70 threads so that when the knots are formed said knots shall be staggered, are mounted upon a slide or carriage 93 which is moved by suitable means transversely of the warps to bring the mechanisms into operative 75 relation with successive threads of the warps.

The means for driving the mechanisms of the machine may be briefly described as follows: On the sleeve 108 is a sheave 106 which may receive motion through any suitable 80 source. On one end of the sleeve 108 is a pinion 109 which meshes with a spur gear 114, said gear being supported by a shaft 114^a in a bracket 114^b on the carriage or slide 93 that supports the tying-in mechanisms. On the same shaft which supports the gear 114 is a gear 115 meshing with a spur gear 120 loose on the knotter shaft 121, the latter shaft being journaled in the bracket 122 on the carriage 93. The cylinder 90 124 rigid on the knotter shaft is provided with a peripheral skew gear 127 meshing with a skew pinion 227 on the bill shaft 226, whereby said bill shaft will be rotated in its cam cylinder 224 to tie the warp threads together in the manner described in the British patent alluded to. 95

The gearing for rotating the knotter shaft in the present instance is as follows: The gear 120 loose on the shaft 121 carries an 100 elliptical gear 120^a which meshes with a similar gear 120^b fast on the shaft 120^c in the bracket 120^d. The shaft 120^c carries an elliptical gear 120^e which meshes with an elliptical gear 120^f on the shaft 121. On the 105 shaft 121 is gear 121^a meshing with a gear 121^b on a shaft which drives a stripper disk 121^c having a stripper hook 121^d. This

stripper hook is substituted for the stripper device 245 247 248 249 shown in said British patent. The rack bars 27 and 51, the shafts 285 and 285^a, the pinions 287 and 287^a, the 5 skew gears 127 and 227, the cam cylinder 224, the bill shaft 226, and the means 206 for holding the ends of the severed threads while said threads are being wrapped around the bill shaft, shown in Fig. 2 of the 10 drawings in this application are similar to corresponding parts in my said British patent.

On the sleeve 108 is a worm gear 1 driving a similar gear 2 on the shaft 3. The 15 shaft 3 is provided with a bevel pinion 4 in mesh with the teeth of a bevel gear 5 on a shaft 6 mounted in the bracket 6^a on the carriage 93. The shaft 6 carries a cam disk 7 having cam grooves 8 and 9 in its upper and 20 lower faces, respectively. In Fig. 1 portions of the bracket 6^a and the gear 5 are broken away to disclose the cam disk 7 below said bracket and gear. Pivoted in the bracket 6^a at 10 and adjacent to the cam disk are the 25 staggering elements, said elements being herein illustrated as arms 11 and 12. These arms 11 and 12 have rearward extensions 13 and 14 provided with pins 15 having rollers 15^a to enter grooves 8 and 9 in the cam disk 7. The portions of the arms distant from the cam disk are provided with terminal fingers 16 and 17 to engage respective warp threads and cause the knots to be staggered.

By reference to Fig. 1 it will be observed 35 that the fingers of the arms are adjacent to the knot-tying mechanism and when in their passive or initial position they lie between the knot-tying mechanism and the warp clamps 20 and 37. The finger 16 operates 40 upon the warp b, the finger 17 operating upon the warp a. When a thread selected from the new warp and a thread selected from the old warp have been moved away from the remaining threads of the warps 45 and into operative relation to the knot-tying mechanism, as shown in Fig. 46 of the British patent, said threads extend across the fingers 16 and 17. When one of the arms 11 and 12 is swung outwardly (away from 50 the knot-tying mechanism) the finger of said arm engages the thread extending across it and pulls a part of said thread out of the holding means 206, thereby increasing the length of the thread between the clamp 20 or 55 37 and the knot-tying mechanism.

In operation, first one arm and then the next or both will act upon successive warp threads. When the arm 11 operates alone, the knot will be formed at a point on the 60 threads nearer the clamp 20 than the clamp 37. When the arm 12 alone acts, the knots will be formed at a point on the threads nearer the clamp 37 than the clamp 20. When both arms act, the knot will be formed 65 at a point the location of which depends

upon the extent of movement of said arms. Each staggering element 11 and 12 will have movement imparted to it so that the thread will be pulled out at about the time it takes its first wrap around the tying bill, the elliptical gears being so arranged that the bill will be rotating relatively slowly during the time that a staggering element is acting upon the threads. As soon as the staggering element has moved out the necessary distance, the speed of the bill shaft is increased so that the knot may be tied quickly. The cam grooves in the cam disk 7 are so arranged that different degrees of movements will be imparted to the staggerers at different times, for example, in Fig. 5 the upper arm 11 is shown as having moved out its full stroke, while the lower arm 12 is stationary. Then in the next tying operation the upper arm moves out two-thirds of a stroke and the lower arm moves out one-third of a stroke. On the next operation the lower arm moves out two-thirds and the upper one-third. The next movement will be effective in moving the lower arm a full stroke while the upper arm remains stationary. It will be seen that the length of thread extending from the clamps 20 37 to the knot-tying mechanism is increased by the arms 11 and 12 by the same amount at each operation.

The operations just enumerated are repeated to provide, in this instance, four rows of staggered knots. When the warps have been tied together, the knots will have the appearance of those represented in Fig. 3 so that the passage of the knots through the eyes of the drop wires, harness, or both, will be accomplished more readily than would be possible were all of the knots in alignment.

I have not described in detail how the warps may be clamped in their frames A and B and presented to the tying mechanism, for all of this is fully described in my said British Patent No. 10,484 of 1905. While I have shown and described the invention as applied to a particular machine, I would have it understood that the invention may partake of many other forms to adapt it to different machines.

I claim as my invention:

1. The combination, with mechanism for tying threads together, of means for longitudinally shifting said threads through different distances into position to be tied.

2. The combination of two clamps; means for loosely holding the ends of threads held by said clamps; a knot-tying mechanism located between said holding means and said clamps; and devices located between said knot-tying mechanism and said clamps for variously positioning the threads with relation to said mechanism so that the knots tied by said mechanism shall be variantly located.

3. The combination of two clamps; means for loosely holding the ends of threads held by said clamps; a knot-tying mechanism located between said holding means and said 5 clamps; two members across which the threads extend between the clamps and the tying mechanism; and means for moving said members against the threads to pull the latter partly out of said holding means.
- 10 4. The combination, with a knot-tying mechanism, of means for supporting the threads to be tied together; two pivoted thread-positioning arms; and means for swinging said arms through various distances.
- 15 5. The combination, with a knot-tying mechanism, of means for supporting the threads to be tied together; two thread-positioning arms pivoted on the same axis, each 20 of said arms having an extension; and a rotatory grooved cam disk operatively connected with said extensions for swinging said arms through various distances.
- 25 6. The combination, with a knot-tying mechanism comprising a tying-bill and means for rotating said bill at non-uniform speed, of means for positioning the thread during the rotation of the bill at low speed.
- 30 7. The combination, with a knot-tying mechanism comprising a tying-bill and means for rotating said bill at non-uniform speed, of means for supporting a thread adjacent to said bill, and means for longitudinally shifting said thread during the rotation of the bill at low speed.
- 35 8. The combination, with a mechanism for tying together two warps, and means for moving said mechanism transversely of the warps, of means for variously positioning 40 threads of one warp with relation to said mechanism so that the knots tied by said mechanism shall be variantly located.
9. The combination, with a warp-tying mechanism, and means for moving said mechanism transversely of the warps, of 45 means for holding the warps to be united; means acting upon threads of one warp to position them with relation to the warp-tying mechanisms; means acting upon threads of the other warp to position them 50 with relation to the warp-tying mechanism; and means for actuating the last mentioned two means in a predetermined order.
10. The combination, with means for supporting two warps, of traveling means for 55 successively uniting the threads of said warps; and means traveling with said uniting means, for variously positioning the threads with relation to said uniting means so that the unions formed by said uniting 60 means shall be variantly located.
11. The combination, with means for supporting two warps, of a warp-uniting mechanism movable in a straight line transversely of the warps; and means for shifting 65 threads longitudinally of the warps to cause the knots to be formed at various points in the length of the warps.
12. The combination with means for supporting two warps, of traveling means for 70 uniting the threads of said warps; and means traveling with said uniting means for longitudinally moving threads of the warps into position to be tied.
13. The combination with means for supporting two warps, of means for uniting the threads of said warps, means for moving said uniting means transversely of the warps, and means for longitudinally moving threads of the warps into position to be tied. 75 80

HOWARD D. COLMAN.
